UNITED STATES PATENT OFFICE.

WATSON R. SMITH, OF JACKSON, MICHIGAN, ASSIGNOR TO VENTILATED CUSHION AND SPRING COMPANY, OF CHICAGO, ILLINOIS, A CORPORATION.

SPRING STRUCTURE.

No. 882,654.

Specification of Letters Patent. Patented March 24, 1908.

Application filed October 29, 1906. Serial No. 341,126.

To all whom it may concern:

Be it known that I, WATSON R. SMITH, a citizen of the United States of America, and a resident of Jackson, in the county of Jackson and State of Michigan, have invented certain new and useful Improvements in Spring Structures, of which the following is a specification.

The main objects of this invention are to provide an improved spring structure particularly adapted for cushions to be used for carriage seats and on upholstered furniture, and also suitable for mattresses and other spring cushions; to provide for the desired yielding resistance to different pressures; and to provide an improved arrangement for connecting together the component parts of the spring structure. These objects are accomplished by the device shown in the accompanying drawings, in which:

Figure 1 is a top plan of a cushion spring constructed according to this invention. Fig. 2 is an end elevation of the same. Fig. 3 is an underneath plan having some of the parts which would otherwise appear in the background, omitted or broken away for the sake of clearness. Fig. 4 is a section on the line 4—4 of Fig. 3.

In the construction shown in the drawings, two sets of furniture springs of respectively different heights are used. The first set consists of long springs 1 and the second set consists of short springs 2. The short springs are secured within and substantially concentric with the long springs 1. Said short springs are of frusto-conical form, while the long springs gradually widen, both toward the top and the bottom. The top convolutions of the long springs lie in contact with each other and are secured together by metal clips 3, and surrounded by a border-frame 4. The bottom convolutions of the long springs are secured to the frame work consisting of the members 5 and the border frame 6. These parts are secured together by means of metallic cross-pieces 7. The cross pieces 7 are provided with struck-up lips 8 which are bent over the bottom convolutions 9 of the short springs 2. Said cross-pieces are also secured to the members 5 and to the border frame 6.

In operation, when used by a person of average weight, the springs 1 ordinarily support the weight upon the cushion, but

in case of a jar, as when used on a vehicle passing over a rough road, the yielding of the springs 1 is at times sufficient to bring the weight of the passenger upon the short springs 2 which then assist the long springs 60 in resisting the jar, and thereby relieve the springing of the cushion and add to the comfort of the passenger. When used by a heavy person, the weight is supported by both sets of springs. The long springs 1 65 support a person of light weight without depressing the short springs 2. The short springs are preferably made of small enough diameter to avoid contact of their convolutions with the convolutions of the long 70 springs when the latter are depressed. This avoids the noise which would otherwise be caused through contact of the convolutions of the two sets of springs.

What I claim as my invention and desire 75 to secure by Letters Patent is:

1. In a spring cushion, the combination of a frame, a plurality of spiral springs secured thereto, a cross-piece secured to and spanning the base of each of said springs, and a 80 plurality of shorter spiral springs, each of the same being secured to one of said cross-pieces within and substantially concentric with one of said longer springs.

2. In a spring cushion, the combination of 85 a frame having a plurality of spiral springs secured thereto, a cross-piece secured to and spanning one of the convolutions of each of said springs, and a plurality of shorter spiral springs each secured to one of said cross- 90 pieces within one of the longer spiral springs.

3. In a spring cushion, the combination of a frame having a plurality of spiral springs secured thereto, a cross-piece secured to and spanning one of the convolutions of each of 95 said springs, each of said cross-pieces being provided with struck-up lips, and a plurality of shorter spiral springs each having one of its convolutions in contact with said cross-piece and secured thereto by means of said 100 lips.

4. In a spring cushion, a frame comprising a series of parallel rods, cross-pieces connecting pairs of said rods, and a plurality of pairs of spiral springs, each pair consisting of a 105 longer and a shorter spring arranged concentrically, the lower ends of the longer springs being attached to said rods, and the lower ends of the shorter springs being attached to said cross-pieces. 110

5. In a spring cushion, a frame comprising a series of parallel rods, sheet metal cross-pieces connecting pairs of said rods, and a plurality of pairs of spiral springs, each pair consisting of a longer and a shorter spring arranged concentrically the lower ends of the longer springs being attached to said rods by means of said cross-pieces, and the lower

ends of the shorter springs being attached to said cross-pieces.

Signed at Chicago this 16 day of October 1906.

WATSON R. SMITH.
